SIGNORS TO ECONOMY DEVICES CORPORATION, OF NEW YORK, N. Y., A CORPORA-
TION OF NEW YORK.

REVERSING-GEAR FOR LOCOMOTIVES.

1,124,589.

Specification of Letters Patent. Patented Jan. 12, 1915.

Application filed December 16, 1913. Serial No. 307,037.

To all whom it may concern:

Be it known that we, WILLIAM F. J. CASEY and GUSTAVE CAVIN, both subjects of the King of Great Britain, and residents 5 of the city of Kingston, in the Province of Ontario and Dominion of Canada, have invented a certain new and useful Improvement in Reversing-Gear for Locomotives, of which improvement the following is a 10 specification.

This invention relates to reversing gear for locomotives, and is an improvement on the gear disclosed in our prior Patent No. 1,082,733, issued December 30, 1913.

15 The object of the present invention is to provide an automatic locking means which will hold the valve gear absolutely rigid.

Another object is to provide means whereby the handle of the control valve will 20 move in the same direction as the ordinary hand reverse lever to produce similar results, so that no confusion can arise in the engineer's mind.

A still further object is to provide a more 25 perfectly balanced and easier operating control valve.

With the reversing gear described in our former patent, there is a certain liability to constant working of the reversing device 30 due to stresses brought to bear by the movement of the valve gear when the engine is running. This is most noticeable in high speed engines and varies in amount according as the device is adjusted to regulate the 35 cut-off of the valves. It has also been found that the hand lever of the control valve operating in the opposite direction necessitated the changing of the valve motion eccentricities in order to obtain the same motion 40 as the hand type of lever. The present invention overcomes these difficulties by providing an automatic lock engaging the piston rod. This lock is raised by fluid pressure automatically admitted from the control valve at the commencement of its operation, so that the piston rod is unlocked 45 for reciprocating movement just as the fluid is admitted through the valve to produce such movement. In order to have the hand 50 lever moved in the same direction as the ordinary reverse levers it is gear connected to the valve.

In the drawings which illustrate the invention:—Figure 1 is a partial longitudinal

section of the operating cylinder showing 55 the locking device attached thereto. Fig. 2 is a front elevation of the control valve complete. Fig. 3 is a front elevation of the valve with cover removed. Fig. 4 is a section on the line 4—4, Fig. 2. Fig. 5 is a 60 front elevation of the power disk. Fig. 6 is a front elevation of the valve body with hand and power disks removed.

Referring more particularly to the drawings, 11 designates a reversing cylinder 65 adapted to contain a piston mounted intermediate the ends of a piston rod 12. One end of this piston rod is connected to the valve gear, while the opposite end is connected by a link 13 with the power lever 14 70 of the control valve mechanism. This arrangement will be clearly understood by reference to the former patent.

In this invention, one of the cylinder heads 15 is provided with a yoke 16 surrounding the piston rod and carrying at its free extremity a small locking cylinder 17 through which the piston rod passes diametrically. The locking cylinder 17 contains a small piston 18, of trunk form, 80 which is slotted at 19 for the passage of the piston rod 12 and a toothed pawl 20 is fitted within it, said pawl being adapted to mesh with teeth 21 formed for a suitable distance on the piston rod. The piston 18 is 85 normally held in depressed position with the pawl 20 engaging the piston rod by a spring 22, compressed between the top of the pawl and the cap 23 of the cylinder. A small piston rod 24 is revolvably connected 90 to the piston 18 and passes out through the cap 23. This rod is provided with a diametrically disposed key 25 sliding in a slot 26 in the cap, so that on occasion the piston may be raised by means of this rod to disengage the pawl from the shaft, and locked in such raised position by partly turning the piston rod, so that the key 25 is out of register with the slots 26 and rests against the outer surface of the cap. Fluid pressure is admitted under the piston 18 through a pipe 27 leading from the control valve whenever the valve is operated. The motive fluid is admitted first through this pipe 27 and raises the small piston 18 to disengage the pawl from the piston rod 12. The motive fluid holds the piston elevated 100 against the action of the spring 22 until the 105

desired adjustment of the valve gear is attained, and the parts of the control valve re-adjust themselves, whereupon the pressure is relieved and the spring forces the piston down until the pawl engages the piston rod 12. If the teeth of the pawl and piston rod do not quite mesh, the slightest movement of the piston rod, (in actual practice about $\frac{1}{16}$ of an inch), brings the teeth into register and the pawl drops. The cylinder 17 is provided at its bottom with a very small exhaust port 28 having an area of not more than one-tenth the area of the supply pipe 27. When the motive fluid is admitted from the control valve, the leakage through this port is not sufficient to prevent the piston being raised and held up, but when the supply of fluid is cut off at the control valve, the leakage through this port very soon allows the piston to drop under the influence of the spring.

The control valve mechanism is in most particulars substantially similar to that described in our Patent No. 1,082,733 aforesaid, and is inclosed in a casing comprising a body 29 and cover 30. The control valve mechanism comprises a manually operated disk 31 and a power operated disk 32, the manual disk having ports 33 formed therethrough, and adapted to register with ports 34 formed in the power disk and positioned over chambers 35 formed in the body. The manual disk also has an exhaust chamber 36 cored out on its under-face and adapted to connect one of the power disk ports 34 with the exhaust outlet. In the present invention, these ports are positioned slightly closer together than in the former invention, so as to leave a portion of each disk free. The power disk is provided with a long eirularly curved port 37 extending therethrough and formed of a length at least as great as the maximum travel of the disks, so that this port will always be in communication with the outlet passage 38 formed in the body and connected to the pipe 27. The manual disk normally covers the power disk port 37, but the lap at each end of the port is preferably much less than the lap at the ports 34, as clearly shown in Fig. 3, so that the port 37 will be uncovered slightly before the ports 34. The manual disk is provided with a pair of ports 39 adapted to uncover the port 37. These ports may be entirely separate or separated merely by a bridge. It will be noted in Fig. 6 that if only the chambers 35 were provided, the power disk would have much less bearing surface on one side of the center than on the other, so that if the disk were kept tightly enough seated to prevent leakage, there would be great friction. To overcome this, as much as possible of the body surface is cut away, thus forming a chamber 40 provided where necessary for the support of

the power disk with bridges 41. This chamber is constantly supplied through a port 42 formed in the power disk, and constantly in register with the manual disk ports 39. The fluid pressure under the disk at this point has the effect of balancing the same and enables the seating of the disk to be kept fluid tight with a minimum of friction. When the manual disk is rotated, the ports 39 thereof register with the port 37 of the power disk, and motive fluid flows through the ports and through the passage 38 and pipe 27, to raise the piston 18 and lift the pawl 20 free of the piston rod 12. All this occurs before any fluid flows through the ports 34 or before there is sufficient flow to cause a reciprocation of the piston, owing to the difference in lap at the ports 34 and 37. As the manual disk which rotates one port 34 is brought into register with a port 33, and the other port 34 with the exhaust chamber 36, so that motive fluid is admitted at one end of the cylinder 11 and permitted to escape at the other end, thus causing reciprocation of the piston rod, which adjusts the valve gear of the engine and at the same time operates through the link 13 and lever 14 to shift the power disk around in the same direction as the manual disk was moved, until the various ports assume their original positions, as shown in Fig. 3, and as described in detail in the former patent.

In most locomotives, the valve gear is connected to the reverse lever between the handle and fulcrum thereof, the handle being drawn back in reversing the engine and pushed forward when going ahead. In our former patent, it will be noted that the power lever and manual levers corresponding to the ordinary reverse lever are arranged with the connections to the reverse gear on the opposite side of the fulcrum from the handle, so that unless the valve motion eccentrics were arranged exactly opposite to common practice the lever would be pushed forward to reverse the engine. This arrangement would cause confusion, and therefore in the present invention the manual lever 43 has been fulcrumed at its lower end at 44, and provided with a toothed quadrant 45 meshing with a second toothed quadrant 46 secured on the stem 47 of the manual disk by means of a pin 48. Thus, the motion is reversed and the manual lever drawn back to reverse the engine in the usual manner, thereby avoiding all possibility of confusion. It will of course be understood that the necessity for this depends entirely on the manner in which the device may be arranged and on the style of reverse lever with which an engine has been formerly equipped, in the event of the installation of this apparatus.

The method of connecting the manual

disk and lever disclosed in our former patent has been found to be too productive of slack motion, and therefore has been replaced by a slightly different structure, as shown in Figs. 3 and 4. The spindle 47 is provided with a pair of arms 50 projecting radially and engaging between lugs 49 formed in pairs diametrically opposite on the manual disk, as shown in Fig. 3. This spindle is recessed at its inner end at 51 to receive a lug 52, centrally disposed on the manual disk, and a spring 53 held in compression between the bottom of the recess and the lug. This spring operates not only to hold the manual disk down on the power disk, but also to hold the inner end of the spindle closely against the cover 30, where a washer 54 is provided to make a fluid tight joint.

Having thus described our invention, what we claim is:—

1. In a device of the character described, the combination with a fluid pressure operated reversing gear including a reciprocating rod of automatically operating rod locking means, fluid pressure operated means arranged to release said locking means prior to the operation of the reversing gear, and manually operated means for setting said locking mechanism permanently in unlocked position.

2. In a device of the character described, the combination of a reversing cylinder; a yoke connected to one end thereof; a piston rod fitted to be reciprocated in the reversing cylinder and guided at the outer end thereof, said rod having a plurality of transversely extending teeth; a locking cylinder extending across the yoke, adjacent to its outer end, and transversely slotted for the passage of the piston rod; a correspondingly slotted piston, of trunk form, fitting said locking cylinder; a pawl fixed in the trunk of said piston and having teeth adapted to engage those of the piston rod of the reversing cylinder; a cap closing one end of the locking cylinder; a spring held in compression between said cap and the pawl; a fluid pressure inlet leading into the locking cylinder opposite the closed end of its piston; and a correspondingly located fluid pressure outlet, of substantially smaller transverse area than the inlet.

3. In a device of the character described, the combination of a reversing cylinder; a yoke connected to one end thereof; a piston rod fitted to be reciprocated in the reversing cylinder and guided at the outer end thereof, said rod having a plurality of transversely extending teeth; a locking cylinder extending across the yoke, adjacent to its outer end, and transversely slotted for the passage of the piston rod; a correspondingly slotted piston, of trunk form, fitting said locking cylinder; a pawl fixed in the trunk of said

piston and having teeth adapted to engage those of the piston rod of the reversing cylinder; a manually revoluble rod connected to said pawl; a transversely slotted cap through which said rod passes and which closes the end of the locking cylinder adjacent to the pawl; a key projecting diametrically from the rod into the cap slots; and means for manually turning the rod to bring said key out of register with said slots and to engage it with the cap for the purpose of holding the pawl out of engagement with the piston rod teeth.

4. In a device of the character described, the combination of a reversing cylinder; a piston rod adapted to be reciprocated by a piston therein; a piston rod locking mechanism; a valve; ports in said valve adapted to simultaneously admit and exhaust motive fluid to and from opposite ends of the reversing cylinder; and a port in said valve, adapted to admit motive fluid to the locking mechanism prior to the admission or release of motive fluid through either of the first mentioned ports, and to maintain the flow of motive fluid to the locking mechanism until admission and release, through the first mentioned ports, have ceased.

5. In a device of the character described, the combination of a reversing cylinder; a piston rod adapted to be reciprocated by a piston therein; a piston rod locking mechanism; a valve device comprising a valve seat having a through port; a valve disk connected for partial revolution by the piston rod, an arcuate port in said disk adapted to maintain opening of the valve seat port during full travel of the disk, a second valve disk, ports therein which are normally out of register with those of the first mentioned disk, a manually operable lever adapted to rotate said second mentioned disk so as to cause the port of the first mentioned disk to be uncovered by one of the ports of the second mentioned disk; and means for admitting motive fluid above said second mentioned disk.

6. In a device of the character described, the combination of a reversing cylinder; a piston rod adapted to be reciprocated by a piston therein; a piston rod locking mechanism; a valve device comprising a chambered body having a valve seat and a through port therein; a valve disk in the valve body connected for partial rotation by the piston rod, ports in said disk adapted to register during full disk travel with the valve body chambers and port, a second valve disk in the valve body having through ports adapted to register with the ports of the first mentioned disk, there being less lap between one of the ports of the first disk and of the second than between the remaining ports thereof, whereby one port of the first disk will be uncovered before the re-

maining ports and covered thereafter; a pipe establishing communication between the least-lapped port and the rod locking mechanism; and pipes connecting the remaining 5 ports with opposite ends of the reversing cylinder.

7. In a device of the character described, the combination of a reversing cylinder; a piston rod adapted to be reciprocated by a 10 piston therein; a piston rod locking mechanism; a valve device comprising a valve body having two chambers on one side of its center and a port on the opposite side, a valve disk in said body having a pair of 15 radially disposed ports communicating with the body chambers and an arcuate port communicating with the body port, a second valve disk having two ports which are normally out register with the radial ports

of the first disk, and two ports normally out 20 of register with the arcuate port thereof, the lap at the ends of the arcuate port being less than the lap at the ends of the radial ports; a pipe establishing communication between the body port and the locking mechanism; a 25 connection for rotating the first valve disk by the piston rod; a manually operable lever journaled in the valve body; a toothed sector carried by said lever; and a similar sector carried by the second valve disk and engaging 30 with the first valve disk.

In witness whereof, we have hereunto set our hands in the presence of two witnesses.

WILLIAM F. J. CASEY.
GUSTAVE CAVIN.
